UNITED STATES PATENT OFFICE.

OTIS C. FUNDERBURK, OF DETROIT, MICHIGAN, ASSIGNOR TO DETROIT LUBRICATOR COMPANY, OF DETROIT, MICHIGAN, A CORPORATION OF MICHIGAN.

CARBURETER.

1,204,423.

Specification of Letters Patent. Patented Nov. 14, 1916.

Application filed May 11, 1914. Serial No. 837,902.

To all whom it may concern:

Be it known that I, OTIS C. FUNDERBURK, a citizen of the United States of America, residing at Detroit, in the county of Wayne and State of Michigan, have invented certain new and useful Improvements in Carbureters, of which the following is a specification, reference being had therein to the accompanying drawings.

10 The invention relates to carbureters of that type in which the discharge of the oil is normally controlled by an adjustable metering pin.

15 It is one of the objects of the invention to obtain an improved construction of adjustment means for the metering pin.

It is a further object to provide auxiliary means for increasing the discharge of oil upon the sudden opening of the throttle, 20 and still further to obtain a construction in which the carbureter automatically adjusts itself to the load independent of the speed of the engine.

25 In the drawings, Figure 1 is a longitudinal section through a carbureter; and Fig. 2 is a sectional elevation at right angles to Fig. 1.

30 A is a casing having a lower portion forming an air inlet chamber B and an upper portion having the mixing chamber C, preferably of pear-shaped form. Arranged concentrically within the chamber B is a cylinder D in which is slidably secured a hollow piston E having the chamber F 35 therein.

35 G is a valve secured to the upper end of the piston E and adapted to rest upon a seat H for closing the secondary air inlet between the chamber B and the mixing chamber C.

40 I is a nozzle arranged concentrically within the piston E and having its upper end terminating within a carburetion chamber G' formed concentrically in the valve G, the top of which is open, the upper portion being flared. The portion of the valve G underlying the chamber G' has screw-threaded connection with the piston, the nozzle I being snugly passed through said portion. Below the upper end of the nozzle, the chamber G' has communication with a plurality of primary air passages H', which at their other extremities open into the air inlet chamber B.

55 J is a tube depending from the piston E

in alignment with the nozzle I and extending into a well or recess K in the lower portion of the casing A, which well is connected by a passage L with the float chamber M.

60

N is the metering pin which is suitably tapered and projects upward into the depending tube J to restrict the inlet. This metering pin is mounted upon a head O which is peripherally grooved to form a 65 rack intermeshing with a pinion P mounted upon a rock-shaft Q.

Q' is a rock-arm secured to the rock-shaft Q and Q² is an adjustable screw at the end of said rock-arm for engaging a stop Q³ 70 upon the casing A.

With the arrangement as thus far described, the oil supplied from the float chamber fills the well K and enters the nozzle I through the opening in the lower end of the depending tube J. The metering pin N serves to variably restrict the opening into the tube J and may be set for minimum opening by an adjustment of the screw Q² 75 which engages the stop Q³. As the tube J depends from the piston E and as the latter is connected with the valve G, it is evident that where the latter valve is lifted by suction in the chamber C the tube J will be also lifted, thereby enlarging the opening around the metering pin so as to permit a greater quantity of oil to be discharged from the nozzle.

80 The construction just described will, under normal conditions, maintain a discharge of oil proportionate to the quantity of air passing through the mixing chamber, as the air cannot enter said chamber without lifting the valve G, which in turn lifts the tube J to enlarge the opening around the metering pin. Where, however, there is a sudden opening of the throttle R, the valve G is frequently thrown violently upward to the limit of its movement and then rebounds to a partially closed position before the oil column can be set in motion. As this would result in a lean mixture, I have provided auxiliary means for increasing the discharge of oil which is operated by a sudden movement of the valve G. This auxiliary means, as specifically shown, comprises a tube S within the hollow piston E, which at its lower end communicates with an opening through the wall of said piston, connecting with an annular channel E' around the pe- 85 90 95 100 105 110

riphery of the piston. The tube S extends upward within the chamber F to a point above the normal hydrostatic level of the oil. T is a tube also within the chamber F in the hollow piston, the lower end of which communicates with an opening through the bottom wall of the piston. U is a port in the nozzle I at the bottom of the chamber F.

- With the construction just described 10 whenever the valve G is moved suddenly upward, as by the sudden opening of the throttle R, the piston E will be lifted and the suction produced by its displacement will be communicated through the tube P to the chamber F, where it will lift the oil in the tube S until it overflows the upper end of said tube and fills the cup-shaped bottom of the chamber F. This will permit the oil to pass through the port U into the nozzle I 15 above the metering pin, so that an increased discharge of oil from said nozzle is obtained.

Where, as in the case of a vehicle running upon a level road, the throttle is opened 20 for the purpose of increasing the speed, the increased air velocity will automatically operate the air valve G and through it control the adjustment of the metering pin N. On the other hand, there are occasions when 25 the speed will be retarded while the throttle remains open, as for instance where the vehicle is climbing a hill. This would result in a decreased velocity of air passing through the mixing chamber and the consequent lowering of the air valve G, which 30 in turn would effect the metering pin adjustment to decrease the quantity of oil. It is, however, desirable to prevent this decrease in the oil supply, as the engine is operating 35 under heavy load, and I have therefore provided the following means for automatically accomplishing such a result. Whenever the air valve G is lifted and maintained open for a short interval, the leakage of oil 40 around the piston E will gradually fill the space in the cylinder D beneath the lifted piston. If the air valve G is gradually lowered, the oil beneath the piston will be forced out in the same manner by leakage 45 about the periphery, but if there is a sudden dropping of the valve, instead of thus passing through the restricted peripheral clearance the oil will be forced upward through the tube T and will overflow into the cup-shaped recess within the piston, from which 50 it will pass through the port U into the discharge nozzle I. Thus any sudden increase in load which tends to check the speed of the engine will automatically increase the richness of the explosive charge 55 so as to maintain or increase the power of the engine.

What I claim as my invention is;—

1. In a carbureter, the combination with 60 a casing containing a mixing chamber, of a

valve controlling the air inlet into said chamber, a nozzle for discharging oil into said chamber, a well normally supplying oil to the nozzle, an auxiliary cup for an auxiliary supply of oil communicating with said nozzle, and means operated by a movement of said valve for filling said cup with oil.

2. In a carbureter, the combination with a casing containing a mixing chamber, of a nozzle for discharging oil into said chamber, a well normally supplying oil to the nozzle, an auxiliary cup for supplying oil to said nozzle, and means other than gravity operating upon a change in the velocity of air passing through said chamber for filling 75 said cup with oil.

3. In a carbureter, the combination with a casing containing a mixing chamber, of a nozzle for discharging oil into said chamber, means for normally supplying oil to 80 said nozzle, a cup for an auxiliary oil supply to said nozzle, and automatic mechanism operating upon a change of velocity of air passing through said chamber for filling 85 said cup.

4. In a carbureter, the combination with a casing containing a mixing chamber, of a nozzle for discharging oil into said chamber, a valve in the air inlet for said chamber, a well normally supplying oil to the 90 nozzle, an auxiliary cup for supplying oil to said nozzle, and means operating upon a sudden movement of said valve for filling 95 said cup.

5. In a carbureter, the combination with 100 a casing containing a mixing chamber, of a nozzle for discharging oil into said chamber, a valve controlling the air inlet into said chamber, means normally operated by the movement of said valve for varying the 105 supply of oil to said nozzle, a cup for an additional supply of oil to said nozzle, and means operating upon a sudden movement of said valve for filling 110 said cup.

6. In a carbureter, the combination with 110 a casing containing an air mixing chamber of a valve controlling the air inlet to said chamber, a nozzle for discharging oil into 115 said chamber, a well normally supplying oil to the nozzle, a hollow piston surrounding said nozzle forming a cup for an auxiliary supply of oil, said piston being connected to said valve, a cylinder in which said piston is located, and means operated by the displacement of said piston in said cylinder 120 for filling said cup with oil.

7. In a carbureter, the combination with a casing containing a mixing chamber, of a valve controlling the air inlet to said chamber, a hollow piston connected to said valve, 125 an oil nozzle passing through said hollow piston and having communication with the chamber therein, a well normally supplying oil to the nozzle a cylinder containing said piston, and means operating upon the sud- 130

den displacement of said piston in said cylinder for filling the chamber of the piston with oil.

8. In a carbureter, the combination with a casing containing a mixing chamber, of a valve controlling the air inlet to said chamber, a hollow piston connected to said valve, a nozzle for discharging oil into said mixing chamber arranged centrally within said hollow piston and having lateral communication with the chamber therein, a cylinder in which said piston is located, a peripheral oil supply connection to said cylinder, a tube connecting with said peripheral oil supply 10 extending upward in the chamber within said piston to a point above the normal hydrostatic level of the oil, and a tube having communication with an opening through the lower end of said piston extending upward 20 within said hollow chamber to a point above the normal hydrostatic level of the oil, whereby a sudden displacement of said piston in either direction will cause an overflow of oil into the piston chamber.
9. In a carbureter, the combination with a casing containing a mixing chamber, of a valve controlling the air inlet to said chamber, a hollow piston connected with said valve, a nozzle for discharging oil into said 30 chamber extending upward within said hollow piston and having lateral communication with the chamber therein, a cylinder in which said piston is located having a restricted peripheral clearance, a peripheral supply connection for oil to said cylinder, and ducts extending respectively from the periphery and from the bottom of said piston to a point within said hollow chamber above the normal hydrostatic level of the 35 oil, for the purpose described.

10. In a carbureter, the combination with a casing containing a mixing chamber, an air inlet connection beneath the same and a cylinder arranged within said air inlet connection, of a valve for closing said air inlet connection, a hollow piston within said cylinder connected to said valve, a nozzle for discharging oil into said mixing chamber arranged centrally within said hollow piston and having lateral communication with the chamber therein, means for supplying oil to the lower end of said nozzle, a metering pin controlling the admission of oil to said nozzle to vary the same upon a movement of said piston, means for supplying oil to said cylinder, and a duct extending from said oil supply to a point within said hollow piston above the normal hydrostatic level of the oil, through which oil is supplied to the chamber within the piston upon a sudden displacement of the latter.

11. In a carbureter, the combination with a casing containing a mixing chamber, an air inlet passage thereto and an oil supply well at the lower end thereof, of a valve con-

trolling said air inlet, a piston connected with said valve engaging said cylinder, a nozzle for discharging oil into said mixing chamber carried by said piston and depending into said well, a metering pin in said well engaging the lower end of said nozzle, a head for adjusting said metering pin slidably engaging the walls of said well and annularly grooved to form a rack, a pinion for engaging said rack, and an adjustable shaft 70 for actuating said pinion to vary the position of adjustment of said metering pin, the head being formed with an opening to receive the lower end of said nozzle.

12. In a carbureter, the combination with a casing containing a mixing chamber, of a nozzle for conducting oil into said chamber, means for normally supplying oil to the nozzle, an auxiliary cup for supplying oil to the nozzle, and means operating upon a sudden rise or fall in pressure in the mixing chamber for filling said cup.

13. In a carbureter, the combination with a casing containing a mixing chamber, of a nozzle for discharging oil into said chamber, a valve controlling the air inlet to said chamber, means normally actuated by a movement of said valve for varying the supply of oil to the nozzle, and means operating upon a sudden increase or decrease of pressure in the mixing chamber for filling said cup.

14. In a carbureter, the combination with a casing formed with a mixing chamber, of a valve controlling the air inlet to said chamber, a nozzle for discharging oil into said chamber, having a primary oil inlet at one extremity controlled by normal movement of the valve, and formed with an intermediate inlet for an auxiliary supply of oil.

15. In a carbureter, the combination with a casing formed with a mixing chamber, of a valve controlling the air inlet to said chamber, a hollow piston rigidly connected with said valve, a cylinder within which the piston is mounted for reciprocation, communication being established between the space within the cylinder underlying the piston and the upper portion of the chamber within the piston, a nozzle extending through the piston having an outlet for discharging oil into the mixing chamber, and formed with primary and auxiliary oil inlets, the latter communicating with the lower portion of the piston chamber, and a source of oil supply having an outlet communicating with the upper portion of the piston chamber, whereby a sudden displacement of the piston in either direction will cause an overflow into the piston chamber from the source of oil supply.

16. In a carbureter, the combination with a casing formed with a mixing chamber, of a valve controlling the air inlet to said chamber, a hollow piston rigidly connected with said valve, a cylinder within which

- the piston is mounted for reciprocation, communication being established between the space within the cylinder underlying the piston and the upper portion of the piston 5 chamber, a nozzle extending through the piston having an outlet for discharging oil into the mixing chamber and formed with primary and auxiliary oil inlets, the latter communicating with the lower portion of the piston chamber, a peripheral oil supply connection to said cylinder and a tube connecting with said peripheral oil supply extending upward within the piston chamber to a point above the normal hydrostatic level 10 of the oil, whereby a sudden displacement of the piston in either direction will cause an overflow of oil into the piston chamber.
17. In a carbureter, the combination with a casing containing a mixing chamber, of a valve controlling the air inlet to said chamber, a hollow piston connected with said valve, a cylinder in which the piston is located, having restricted peripheral clearance, communication being established between the space underlying the piston within the cylinder and the upper portion of the piston interior, a nozzle extending through the piston having an outlet for discharging oil into the mixing chamber, and formed 20 with primary and auxiliary oil inlets, the latter communicating with the lower portion of the piston interior, and a source of oil supply having communication with the upper portion of the piston interior whereby a sudden displacement of the piston in either direction will cause an overflow in to the piston chamber from said source of oil supply.
18. In a carbureter, the combination with a casing containing a mixing chamber, of a valve controlling the air inlet to said chamber, a hollow piston connected with said valve, a cylinder in which the piston is located, portions of the piston and cylinder 40 being spaced from each other to form an oil reservoir, a restricted peripheral clearance being provided between the piston and cylinder from the oil reservoir downward, communication being established between the space underlying the piston and the upper portion of the piston interior, a nozzle extending through the piston having an outlet for discharging oil into the mixing chamber, and formed with primary and auxiliary 50 inlets, the latter communicating with the lower portion of the piston interior, and a duct communicating at one extremity with said oil reservoir and opening at its other extremity within the piston chamber above the normal hydrostatic level of the oil, whereby a sudden displacement of the piston in either direction will cause a discharge from the oil reservoir into the piston chamber.
19. In a carbureter, the combination with a casing containing a mixing chamber, of a valve controlling the air inlet to said chamber, a nozzle for discharging oil into said chamber, a well normally supplying oil to the nozzle, an auxiliary oil supply cup communicating with the nozzle, an oil reservoir having an outlet to said cup above the normal hydrostatic level of the oil, and means operated by a movement of said valve for lowering the hydrostatic pressure within the auxiliary oil supply cups, producing an overflow from the oil reservoir into said cup.
20. In a carbureter, the combination with a casing containing a mixing chamber, of a nozzle for discharging oil into said chamber, a well normally supplying oil to the nozzle, an auxiliary oil supply cup communicating with the nozzle, an oil reservoir having an outlet into said cup above the normal hydrostatic level of the oil, and means operating upon a change in the velocity of air passing through the mixing chamber, for lowering the hydrostatic pressure within the auxiliary supply cup, thereby producing an overflow into said cup from the oil reservoir.
21. In a carbureter, the combination with a casing containing a mixing chamber, of a nozzle for discharging oil into said chamber, means for normally supplying oil to the nozzle, a cup for an auxiliary oil supply to said nozzle, a member subjected to an intermittent motion actuated by changes in the velocity of air passing through the mixing chamber, and means dependent upon said motion for delivering an auxiliary supply of oil to said cup.
